DEMOUNTABLE SHOWCASE

Leo Roselyn, San Francisco, Calif.

Application February 5, 1946, Serial No. 645,642

4 Claims. (Cl. 312—114)

1

The invention, in general, relates to merchandise display units and more particularly relates to an improved display case having enlarged visibility, enlarged space for reception of merchandise and yet being rugged and durable with features affording the protection of the contained merchandise from theft or from damage by accumulation of dust.

Heretofore, show case construction largely has been confined to the provision of relatively heavy bases, frames and studs or supports to which glass or other transparent panels are permanently fitted or affixed by means of cement or other relatively infusible adhesive. The foregoing type of construction has been applied both in the construction of small and large show cases, and is subject to a major disadvantage in that whenever a panel is broken or loosened from its supports it is necessary to remove the entire unit from service for repairing the damage at some remote repair shop usually taking hours to remove, repair and re-install in service. Often-times, because of faulty cements or adhesives, the panels of such more or less permanently built show cases become so loose in their fittings that increasing quantities of dust enter the cases thus seriously damaging or lessening the value of the goods on display therein.

A primary object of my invention is to provide a dust-proof, tamper-proof, tight-fitting and durable show case having demountable features for readily disassembling and reassembling the unit at will and with dispatch.

Another object of the present invention is to provide an improved show case of the indicated nature which is additionally characterized by its enlarged visibility, enlarged display space for contained merchandise and yet is rugged, durable and inexpensive to manufacture and maintain.

A still further object of the invention is to provide an improved show case of the aforementioned character which affords ready and facile demountability of one or more of its panels or other parts at will.

Another object of the invention is to provide an improved demountable show case of the indicated nature affording simple and inexpensive means for rendering the case tamper-proof.

The foregoing and other objects are attained in a preferred and certain modified embodiments of my invention which are illustrated in the accompanying drawings. It is to be understood that I am not to be limited to the precise embodiments shown, nor to the precise arrangement of the several parts of such embodiments,

2

as my invention, as defined in the appended claims, can be embodied in a plurality and variety of forms.

Referring to the drawings:

5 Figure 1 is a perspective view of a preferred embodiment of my invention, as exemplified in a generally rectangular display case.

Figure 2 is a broken transverse sectional elevational view of the embodiment of my invention shown in Figure 1.

Figure 3 is a broken longitudinal sectional view of a preferred embodiment of the invention, as exemplified in a case having an obliquely disposed panel.

15 Figure 4 is a broken elevational view, on an enlarged scale, of the rim strip and panel supporting post basic structure forming elements of the preferred embodiment of my invention.

Figure 5 is a sectional detail of a typical panel supporting post for aligned panels, in juxtaposition, in the preferred embodiment of the invention.

20 Figure 6 is a fragmentary development of the preferred embodiment of my invention illustrating the demountability of the same.

Figure 7 is an enlarged detail, partly in section, and partly in elevation, of certain elements of the preferred embodiment of the invention.

Figure 8 is a perspective view of a locking element employed in the preferred embodiment of the invention.

25 Figure 9 is a detailed sectional view illustrating the locking element in operative position.

Figure 10 is a sectional detail showing a type of panel cushioning means applicable to a panel post and top frame in the preferred embodiment of the invention.

30 Figure 11 is a fragmentary sectional elevational view of a preferred embodiment of the invention, as exemplified in a display case provided with a slanting panel.

Figure 12 is a broken, transverse sectional elevational view illustrating another type of cushioning means applied to the panel supporting posts forming a part of the preferred embodiment of the invention.

35 Fig. 13 is a sectional detail illustrating the preferred mode of applying panel cushioning means to a panel supporting post in the preferred embodiment of my invention.

40 In its preferred form, the demountable show case of my invention preferably comprises a base in which a plurality of transparent side and end panels are mounted, a closure frame on one side of said base, a plurality of relatively narrow panel

supporting posts detachably secured to said base at the junctures of adjacent panels; said posts being adapted rigidly but releasably to support said panels in upright positions, together with a continuous channelled rim strip removably seated on the tops of said side and end panels and on said closure frame, a transparent lid removably seated on said rim strip, means for locking said posts, said panels, said rim strip and said lid securely together, and a door movably mounted in said closure frame for gaining access to the interior of the case.

As illustrated particularly in Figures 1, 2, 6 and 7 of the annexed drawings, I provide a suitably shaped base 11 in my improved demountable show case which includes an outer rim 12 defining legs for the case and a flat, horizontally disposed bottom 13 so cut or formed as to provide a continuous groove 14 around the perimeter thereof between the rim 12 and the bottom 13 for the reception of the case panels. At the back of the base 11, and preferably integral therewith, I provide an upright closure frame 15 which is so formed as to provide therein a groove 16 adjacent each end thereof for receiving the ends of the side case panels and also to provide a cut-away portion at the top thereof to furnish a seat 17 for the removable lid strip of the case, as well as grooves 18 and 19, see Figure 2, to accommodate movable doors 21 and 22 for gaining access to the case. Of course, the continuous groove 14 may be cut to any width and depth to accommodate any desired thickness and weight of transparent panels provided for the display unit. While I preferably fabricate the base 11 and its integral closure frame 15 from wood, these elements can be made from plastic or other suitable materials capable of being grooved and shaped.

In accordance with my invention, as exemplified in a generally rectangular-shaped show case depicted in Figure 1 of the drawings, I provide a relatively long front transparent panel 26, and a pair of side transparent panels 27 and 28 as well as a top transparent panel 29 for the case. The front panel 26 is preferably removably supported in upright position by means of a portion of the continuous groove 14 of the base 11 as well as by means of a portion of a removable lid strip 31, more particularly hereinafter described, and by means of panel supporting corner posts 32 and 33 also more particularly herein-after described. The side panels 27 and 28 of the case are removably supported in upright positions by portions of the continuous groove 14 of the base 11, by portions of the removable lid strip 31, and by the corner posts 32 and 33 as well as by the grooves 16 formed in the closure frame 15 of the base 11. Preferably, all of the transparent panels 26, 27, 28 and 29 are fabricated of clear glass of uniform thin section.

To the end that the improved show case of the present invention will have increased visibility, the preferred embodiment of my invention is provided with relatively narrow panel supporting posts which are as few in number as ruggedness and rigidity will permit. In the rectangular-shaped case depicted in Figure 1 of the drawings, but two panel supporting posts are required and these are the corner posts 32 and 33 which are securely fastened not only to the base 11 but to the lid strip 31. In the pentagon-shaped case depicted in Figure 3 of the drawings, three panel supporting posts are required of which one is a corner post and two are posts provided between the obliquely disposed panel 26a and the front

panel 26 and side panel 27. In general, the corner posts 32 and 33 as well as the lid strip 31 are formed substantially similar although the corner posts are augmented with lip flanges hereinafter mentioned for removably securing such posts to the lid strip and to the base. The general formation of the lid strip 31 and the corner posts 32 and 33 is depicted in Figure 4 of the drawings, while the view of Figure 7 shows the lip flanges 10 on the corner posts, above mentioned. With particular reference to Figures 4 and 7, it will be observed that the lid strip 31 and corner posts 32 and 33 are fabricated of relatively thin section material, preferably bendable metal such as 15 sheet steel, bronze, brass, stainless steel or other suitable metal, and that each strip and post is so formed as to provide a channel section 34 of which one side 36 thereof extends at a right angle to base 37 while the other side 38 thereof also 20 extends at a right angle to base 37 but is turned upon itself to form a flange 38a. The base 37 and sides 36 and 38 of the channel section 34 of the strip or corner posts define a channel for the reception of the end of a panel, and the in-turned flange 38a of side 38 affords a resilient seat for the panel within the channel of the strip or post. The side 36 of the channel section 34 of the strip or post is extended at substantially a right angle to provide a lateral, integral member 39 which also is turned upon itself to provide an out-turned flange 39a. The exterior of the side 36 and the exterior of the lateral member 39 of the strip or post afford seats for the end of another or adjacent panel, and by 35 reason of the out-turned flange 39a on lateral member 39, the latter affords a resilient seat for such adjacent panel. Thus, the lid strip 31 and the corner posts 32 and 33 are so formed as to provide seats for two adjacent panels disposed 40 at right angles to one another, such as the panels 26 and 27, or the panels 26 and 28 of the rectangular-shaped display case depicted in Figure 1 of the drawings.

In order to eliminate all possibility of chipping or cracking of panels at the ends thereof, I provide cushioning means for the lid strip 31 and the corner posts 32 and 33, as well as all other panel supporting posts of the improved case. To this end, and as illustrated in Figure 13 of the accompanying drawings, felt flocking is applied, preferably by means of spraying, to those portions of the surfaces of the posts 31 which are engaged by the panels; such felt flocking being indicated in Figure 13 by the dotted lines and being sprayed onto the metal after the latter has been treated with an adhesive sizing.

An alternative panel cushioning means is illustrated in Figure 10 of the accompanying drawings wherein I have depicted the top panel 29, in 60 fragmentary, dotted line showing, in position seated against the side and on the laterally extending member of the rim strip 31, with an intervening strip 41 of fabric, such as felt, adhesively fastened to the exterior surfaces on such side and lateral extending member. As shown, the exposed extremity of the fabric strip 41 initially is permitted to depend from the rim strip and when an adjacent panel, such as the side panel 26 or 27, not shown in this view, is placed 65 into position within the channel section of the rim strip the depending extremity 42 of the fabric strip 41 will be pushed within the channel section of the strip 31 between the panel and the rim strip 31. This same alternative cushioning means 70 can be applied to the corner and other panel sup-

porting posts of the case. The cushioning effect of the fabric 41, plus the resilient seats afforded by the flanges 38a and 39a of the rim strip 31 as well as the corner and other supporting posts, will protect the transparent panels from likelihood of chipping or cracking.

Each of the corner posts 32 and 33, as well as other panel supporting posts hereinafter described, is provided with convenient means for removably fastening the posts to the base 11 and to the lid strip 31. To this end, the lateral member 39 of the corner posts 32 and 33, is out-turned at its longitudinal extremities to provide lips 43 which are formed with a suitable hole for passing screws 45 whereby the posts may be removably attached to the base 11 and the strip 31, the latter conveniently being provided with suitable holes 31a at the corners for accommodating the screws 45.

It is to be observed that, other than the one corner post, the panel supporting posts for the pentagon-shaped display case depicted in Figure 3 of the drawings are differently constructed and this is likewise true with respect to display cases of my present improvement having a relatively long front wherein I provide two rather than one front transparent panels with an intermediate panel supporting post between the two aligned front panels, as indicated in Figure 5 of the drawings. In the case of the pentagon-shaped embodiment of my invention depicted in Figure 3, I provide in addition to the front transparent panel 26 and the side panels 27 and 28, an obliquely disposed upright transparent panel 26a intermediate the side panel 27 and the front panel 26. To the end that such obliquely disposed panel 26a be properly supported, two similar panel supporting posts 32b are provided at the junctures of panel 26a with the front panel 26 and the side panel 27; each of the panel supporting posts 32b preferably comprising a retainer member 51 and a retained member 52 which are fabricated from bendable sheet metal, such as sheet steel. The retainer member 51 is so formed as to provide opposed webs 53 and 54 having their extremities inturned to afford resilient sides of oppositely facing channels in which the adjacent ends of panels 26 and 26a are received. The retained member 52 of each of the panel supporting posts 32b preferably is so formed from bendable metal as above described, to provide a substantially straight or flat portion terminating in an angularly disposed element 56 at one extremity thereof which is adapted to be wedge-fitted into the inturned web 54 of the retainer member 51 of the post 32b, while the other extremity of the retained member 52 is turned upon itself to afford a resilient seat for the panels 26 and 26a; such seats 57 of members 52 constituting the remaining sides of the oppositely facing channels above mentioned into which the adjacent ends of panels 26 and 26a are received when the case is set up. Integral, laterally extending lips 58, provided with a hole for passing a screw 59, are formed on the top and bottom of the retained member 52 of the post 32b in order that such posts may be detachably secured to the bottom 13 of the base 11, as well as the rim strip 31, and it is to be understood that the shapes of the retainer member 51 and retained member 52 are such that the webs 53 and 54 of member 51 will parallel the panels 26 and 26a when the posts 32b are set up and that the extremity of seat 57 of retained member 52 will span the gap between the two panels 26 and 26a, as illustrated in Figure 3. It is of course to be

understood that the panel supporting posts 32, 32a and 32b are all cut or stamped to equal lengths.

In Figure 5 of the drawings, I have illustrated a modified embodiment of panel supporting post 32a for use in connection with a display case of my improvement having a relatively long front and wherein two adjacently disposed and aligned front panels 26 and 26' are provided. The panel supporting post 32a is substantially the same construction as the post 32b in that it comprises a retainer member 61 and a retained member 62, with the retainer member formed from a single strip of bendable metal that is shaped to provide a straight back portion with inturned extremities 63 and 64 affording resilient sides of oppositely facing channels in which the adjacently disposed panels 26 and 26' are received. The retained member 62 is preferably also formed from a single strip of bendable metal and comprises a straight portion terminating at one extremity in a lateral element extending at a right angle to the straight portion; such lateral element 66 being adapted to be wedge-fitted into the inturned extremity 64 of the retainer member 61, while the other extremity 67 of the straight portion of retained member 62 extends in both directions at substantially right angles to the straight portion to provide the remaining sides of the above-mentioned channels in which the adjacent ends of panels 26 and 26' are received when the case is set up. The extremity 67 of retained member 62 of the panel supporting post 32a is so formed as to provide a laterally extending lip 68 on both longitudinal extremities thereof, which lips 68 are formed with holes therein for passing screws 69 for detachably fastening the post 32a to the bottom 13 of the base 11 and the rim strip 31 of the case.

The improved demountable display case of the present invention includes means rendering the case tamper-proof and incapable of disassembly except by those rightfully having access to the interior of the case. The tamper-proof means that I preferably provide is illustrated in Figures 8 and 9 of the annexed drawings and comprises a clip 71 so stamped from a sheet of bendable metal as to afford therein an angular-shaped channel 72 which includes seats 73 there-in for the reception of the top transparent panel 29 of the case, and also providing a depending skirt 74 thereon which is adapted to be turned back under the rim strip 31. One of these clips 71 is slipped over the panel 29, at each of its four corners, before the panel 29 is seated on the lid strip. Thereafter, each of the clips 71 is placed in operative position to render the case tamper-proof by inserting the hand into the case and bending back the skirt 74 of each clip so that it will underlie the lower or inner side of the strip 31 and bear against the same. To release the latching effect of the clips 71 for the purpose of disassembling the case, it is only necessary to reach within the case and bend the skirts 74 thereof downward to the dotted line position indicated in Figure 9 of the drawings.

A modification of the present invention is illustrated in Figure 11 of the drawings wherein I have depicted my improvement as exemplified in a case having a slanting front panel 126. To the end that the slanting panel is properly supported, the lid strip 31 is modified only to the extent of extending one side or arm 38 thereof at an oblique angle rather than at a right angle as in the case of the lid strip construction for

the modification shown in Figures 1 to 10 inclusive. Similarly, the corner posts 32 and 33, as well as any intermediate panel supporting posts that may be provided, such as the posts 32a and 32b, are also slightly modified so that the channel portions thereof will accommodate the inclination of the slanting front panel 126 and the disposition of the posts arranged also to correspond to the slanting of such front panel of the case.

It is to be understood that the appended claims are to be accorded a range of equivalents commensurate in scope with the advance made over the prior art.

I claim:

1. A demountable show case comprising a base, a closure frame on the back of said base and extending normal thereto, movable doors mounted in said closure frame for opening and closing the case, a plurality of transparent panels removably mounted on said base, a lid strip removably seated on the top of said panels and on the top of said closure frame, a top transparent panel removably seated on said lid strip, and locking means comprising a plurality of clips with bendable depending skirts on said top panel for latching the case against disassembly unless access to the interior thereof is gained through said doors; said skirts of said clips being adapted to be bent to bring the same into bearing engagement with the inner side of said lid strip.

2. In a tamper-proof demountable show case including a panel and a lid strip, a locking clip at the juncture of the panel and the lid strip comprising a stamping having an angular-shaped channel formed therein, and a depending bendable skirt thereon; said skirt being adapted to be bent back upon itself to clamp the clip in operative position over the top of the panel and bottom of a lid strip.

3. A tamper-proof demountable show case comprising a base, a plurality of transparent panels extending normal to said base and ar-

5 ranged in juxtaposition, a panel supporting post at the junctures of adjacently disposed panels, a channeled lid strip fitted to the tops of said panels, a seat on said lid strip, a closure frame on said base and extending normal thereto and spanning the exposed ends of said panels; said closure frame having grooves therein for removably receiving the exposed ends of said panels, movable doors mounted in said closure 10 frame for opening and closing the case, and a locking clip on said top panel for locking the case against disassembly by clamping the top panel to said lid strip within the case.

15 4. A demountable show case comprising a base, a plurality of panels resting on and standing normal to said base, a channeled lid strip fitting the tops of said panels, a top panel removably seated on said lid strip, channelled posts disposed between said plurality of panels and 20 extending normal to said base for retaining said panels in juxtaposition, and locking means fitted between said lid strip and the tops of said plurality of panels; said locking means being bendable and being adapted to be bent 25 into engagement with said lid strip.
